Inventor

Ralph Anton Nemanich

UNITED STATES PATENT OFFICE.

RALPH A. NEMANICH, OF JOLIET, ILLINOIS.

PORTABLE FOLDING SHOE-SHINE STAND.

Application filed April 29, 1922. Serial No. 557,443.

To all whom it may concern:

Be it known that I, RALPH A. NEMANICH, a citizen of the United States, residing at Joliet, in the county of Will and State of Illinois, have invented new and useful Improvements in Portable Folding Shoe-Shine Stands, of which the following is a specification.

This invention relates to portable shoe shining equipment, carried by boys in most every town and city, whereby a person can have his shoes shined most anywhere without the necessity of having to look for a shining parlor.

An important and more specific object is the provision of a device of this character constructed so that a person may have both shoes on the stand at one time, thereby avoiding the objectional changing of one foot and then the other on the stand, as on the present one-foot stands. Still it may be carried, folded, in the size of the present one-foot stand, together with all equipment therein.

An additional object is the provision of a device of this character which will be very simple and inexpensive in manufacture, highly efficient in use, durable in service, and a general improvement in the art.

With the above and other objects and advantages in view, the invention consists in the details of construction to be hereinafter more fully described and claimed, and illustrated in the accompanying drawing, in which—

Figure 1 is a perspective showing my device disposed upon a floor, opened, as in actual use. The floor being merely suggested diagrammatically.

Figure 2 is a perspective showing my device closed, as when carried, not in use.

Referring more particularly to the drawing, A designates the floor, and B designates my device as a whole.

In carrying out my invention I provide two separate rectangular boxes 10 and 11,

consisting of two ends, one top piece and one side piece to each box, formed of either one-half inch thick hardwood or light sheet metal, each box twelve inches long, four 50 and one-half inches high and four and one-half inches wide. These two boxes are held together by hinges 12, which permit box 11 to close into box 10. To accomplish this the two ends 13 of box 11 are each placed inward one-half inch to permit their passage by the sides 14 of box 10. Disposed on top of each box is a foot stand 15, preferably of cast iron or pressed out of sheet iron, to receive the shoes for the shining. When box 60 is not in use and closed a small hook and staple on the two sides will keep it firmly closed and shining equipment safely inside.

While I have shown and described the preferred embodiment of my invention, it is 65 of course to be understood that I reserve the right to make such changes in the form, construction, and arrangement of parts as will not depart from the spirit of the invention or the scope of the subjoining 70 claims.

Having thus described my invention 1 claim:

1. A portable shoe shining stand, comprising two supporting members one adapted to 75 be contained within the other and said members each comprising an upper, a side and two end plates, foot rests positioned upon said upper plates, and said members being hingedly connected along adjacent edges of 80 said upper plates whereby said members may be swung to extended or folded position.

2. A shoe shining stand comprising two members providing when in operative position supporting means mounting co-planar 85 upper plates arranged adjacent each other, foot rests positioned on said upper plates, and said members being constructed to fold one within the other to form a compact closure readily portable.

In testimony whereof I affix my signature.
RALPH A. NEMANICH.
